UNITED STATES PATENT OFFICE.

MARION R. BOWE, OF PHILADELPHIA, PENNSYLVANIA, ASSIGNOR OF ONE-HALF TO
WILLIAM D. HARRIS, OF PHILADELPHIA, PENNSYLVANIA.

BOILER-CLEANING DEVICE.

Application filed March 3, 1922. Serial No. 540,684.

This invention relates to improvements in devices for cleaning the tubes of fire tube boilers wherein the cleaning is effected by steam directed by nozzles to and through the tubes.

An object of my invention is to provide a cleaning device of novel, simple and efficient construction in which the steam supplied to the cleaning nozzles may be superheated by the products of combustion issuing from boiler tubes, ensuring the discharge of dry steam from the nozzles. Another object of the invention is to provide means acting automatically for the elimination of water or condensation from the cleaning device after each cleaning operation. Another object is to provide a novel means to support the device on the boiler housing doors in front of the boiler in a manner to permit it to be readily adjusted to bring its steam discharging nozzles either closer to or farther from the forward ends of the boiler tubes and to permit it to be adjusted vertically to bring the nozzles into alignment with the tubes; and a further object of the invention is to provide an improved form of nozzle for directing the steam to all parts of a tube being cleaned.

With the foregoing objects in view, the invention consists in the novel construction, combination and arrangement of parts hereinafter described and claimed.

In the accompanying drawings, illustrating my invention,

Figure 1 is a front view of a portion of a boiler provided with a cleaning device embodying my invention, one of the doors of the housing being shown in the open position.

Figure 2 is a longitudinal, vertical section through the forward portion of the boiler housing.

Figure 3 is a view of one of the steam headers of the cleaning device and parts attached thereto.

Figure 4 is a longitudinal section through one of the nozzles, on line 4-4 of Fig. 5.

Figure 5 is an end view of the nozzle.

Figure 6 is a vertical section through the steam separator.

Figure 7 is a rear view of one of the headers and the steam separator formed thereon.

Figure 8 is a vertical section through the header, on line 8-8 of Fig. 7.

Figure 9 is a horizontal section through

the steam separator, on line 9-9 of Fig. 6.

Figure 10 is a section through the valve for controlling the drain pipe for the water of condensation.

Referring to the drawings, 2 designates a fire tube boiler and 3 a housing enclosing the same. The boiler 2 is provided with the usual fire tubes 5 extending longitudinally therethrough and open at both ends. The housing 3 is provided with a fire box 6, a passage 7 leading therefrom back beneath the boiler to the rearward ends of the tubes 5, and a passage 10 extending in front of the forward ends of the tubes 5 and leading back over the boiler to a suitable chimney or stack. The products of combustion from the fire box 6 are adapted to pass therefrom back through the passage 7, then forwardly through the boiler tubes 5 and then up and back through the passage 10, as is well known in boilers of this type.

The front wall of the passage 10 or housing 3 is provided with an opening 11 in front of the boiler 2, and the opening 11 is normally closed by a pair of doors 12 which are hinged, at 13, to the main walls of the housing 3, and which may be opened to afford access to the boiler 2 when desired.

The parts thus far described are common and well known to persons skilled in this art, and no detailed description thereof is deemed necessary herein.

Arranged within the passage 10 between the front end of the boiler 2 and the doors 12 are two aligned, horizontally extending steam headers 14 which are located centrally of the end of the boiler. Each door 12 carries a header 14; and as the construction of each header and its connected parts and their relation to its door 12, the boiler 2 and housing 3 are the same, a description of one will suffice for both, as follows:

The header 14 is secured near its end to two angle plates 15 by U-bolts 16, and each angle plate 15 is connected to the door 12 by two horizontal rods 17 and an upwardly and outwardly inclined rod 18. The inner ends of the rods 17 penetrate the angle plate 15 and are secured thereto by nuts screwed on to the rods and engaging opposite surfaces of the angle plate. The upper end portion of each rod 18 extends through the door 12 and has a nut 19 screwed thereon and engaging the top of the door 12. It will thus be understood that the rods 18 take the

weight of the header 14 and support the same and that by turning the nuts 19 the header 14 may be raised or lowered, as desired. The angle plates 15 are provided with vertical slots 20 through which the horizontal rods 17 extend to permit the header 14 to be adjusted vertically, as above described. The outer end portions of the rods 17 extend through the door 12 and have suitable heads on the outer ends thereof by means of which they may be adjusted. The rods 17 are also provided with nuts 21 which engage the inner and outer surfaces of the door 12. By adjusting the nuts 21 the header 14 may be adjusted toward and from the forward ends of the boiler tubes 5, as desired.

The casting forming the header 14 has an enlarged hollow portion 22 extending downwardly therefrom and toward the boiler 2 and forming a steam separator having a separating chamber 23 therein. The upper rearward portion of the separator is connected to a pipe connection 24 extending between it and a central steam supply pipe 25 leading from the boiler 2. The pipe connection 24 is provided with a suitable controlling valve 26 adapted to be opened and closed by means of a pull chain 27 to supply steam to the separator 22 when desired.

The upper forward portion of the separating chamber 23 opens into the steam header 14 which extends outwardly from each side of the steam separator 22, and a baffle wall 28 extends downwardly within the chamber 23 from the top wall thereof between the steam inlet opening 29 and the header 14, and the lower end of the baffle wall 28 has a rearwardly directed lip or flange 30 thereon to deflect the incoming steam against the ribbed or corrugated rearwardly bulging wall 31 of the separator 22 and prevent the direct passage of the steam to the header 14. Extending across the chamber 23 below and spaced from the bottom of the baffle wall 28 is a partition like grate 32 formed by narrow bars having narrow spaces between them to permit water of condensation to pass and to interfere in some measure with the passage of steam below the same as the steam passes around the bottom of the wall 28 on its way to the header 14. The separator 22 is made tapering below the grate 32 and has a discharge outlet opening 33 in the bottom thereof for water of condensation. The opening 33 communicates with a drain pipe 34 which extends downwardly from the separator and through the door 12 to a suitable point of discharge.

The drain pipe 34 is controlled by a globe valve 35 of novel construction, as shown in detail in Fig. 10. The valve head or valve proper 36 of this valve 35 is carried by a reciprocative stem 37 which extends outwardly from the valve casing and has an

adjustable head 38 screwed on to the outer end thereof. Encircling the stem 37 between the head 38 and the casing of the valve 35 is a helical spring 39 which holds the valve 36 normally in the open position away from its seat 40 and against which the valve 36 may be moved to its closed position against the seat. When the valve is thus closed it is adapted to be held closed by steam pressure acting against the same in opposition to the spring 39; and when the steam pressure is removed, the spring 39 is adapted automatically to open the valve for a purpose hereinafter explained. The valve head 36 has a small passage 41 extending through the same which is too small to interfere with the steam pressure holding the valve in the closed position and which is provided to permit a small quantity of water of condensation to pass the valve head 36 when it is in the closed position.

Screwed into projecting bosses on the forward wall of the header 14 is a row of hollow fittings 42 which communicate with the header; and screwed into the top and bottom of each fitting 42 are upwardly and downwardly extending alined pipes 43 closed at their free ends. The pipes 43 communicate with the fittings 42 and are arranged directly in front of the vertical rows of boiler tubes 5 behind the door 12. The pipes 43 are provided with horizontally extending pipes 44 which correspond in number with the tubes 5 of the vertical row thereof in front of which the pipes 43 are located, and the pipes 43 are in axial alinement with the tubes 5. The inner or rearward ends of the pipes 44 are provided with steam discharging nozzles 45 each of which comprises a hollow head 46 having a central outwardly extending projection 47 provided with a central steam discharging passage 48. The head 46 is also provided with an outwardly flared groove 49 in its outer wall around the projection 47, and with passages 50 connecting the groove 49 with the interior of the head 46. The central passage 48 is designed to discharge steam with great force along and against the rear or distant interior surfaces of the fire tubes 5, and the passages 50 and flaring groove 49 are designed to discharge steam with great force along and against the forward or near interior surfaces of the tubes 5.

Each fitting 42 is provided with a valve head 51 which controls communication between the header 14 and the pipes 43 extending from the fitting. Each valve head 51 is fitted to a seat 52 formed on the inner end of the fitting 42, and each valve head 51 is carried by a stem 53 which is slidable in its fitting 42. Each valve stem 53 projects outwardly from its fitting 42 and is embraced by the bifurcated upper end of a lever 54 which is fulcrumed, at 55, on an

arm extending from its fitting 42. The bifurcated end of the lever 54 is arranged between two collars 56 fixed on the valve stem 53, so that the lever 54 may engage the 5 collars and move the valve stem and head 51 when the lever 54 is moved, and so that the stem 53 and head 51 may be free to turn relatively to the lever 54 for wearing and seating purposes. The lower arm of each lever 10 54 has a rod 57 secured thereon and projecting outwardly therefrom through a small opening in the adjacent door 12. Each rod 57 has a suitable head 58 on the outer end thereof by means of which the rod 57 may be 15 operated by hand to move the lever 54 to move its valve head 51 to the open and closed position, as desired. When the valve head 51 is moved to the closed position, it is held tight against its seat 52 by the steam pressure 20 within the header 14.

It will be observed that the tube cleaning device is divided on a vertical plane extending longitudinally through the center of the boiler into two like sections on the respective sides of the said plane, and that each section is supplied with steam from the central pipe 25 to clean the tubes on its side of the said plane. The two sections are alike excepting that they are made right 25 and left, as shown; and as each section is 30 operated the same as the other, a description of the operation of one will suffice for both as follows:

When it is desired to clean the tubes 5 back of a cleaning section, the valve 26 is 35 opened, permitting steam from the boiler 2 to enter the steam separator 22 through the pipe connection 24 and force out through the pipe 34 and open valve 35 all water of condensation that may be present within the 40 separator and the drain pipe 34. After this water of condensation is forced out, the valve 35 is pushed shut and the steam pressure between it and the valve 26 holds the valve 35 in the closed position against the 45 action of the spring 39. The rods 57 are then successively pulled outwardly and afterwards released or pushed inwardly to open and close the valves 51, one at a time. 50 While each valve 51 is held in the open position, steam is discharged from the vertical row of nozzles 45 controlled thereby and the vertical row of tubes back of the nozzles is cleaned by the steam, as previously explained. After the vertical rows of 55 tubes 5 have been thus cleaned, the valve 26 is closed and subsequently the reduced steam pressure within the separator 22 and pipe 34 permits the spring 39 to open the valve 35 for a succeeding tube cleaning 60 operation.

The construction of the steam separator and the relation of the parts thereof to the boiler and to the other parts of cleaning device forms an important part of my in-

vention because the hot gases or fire issuing from the tubes 5 strikes the separator and superheats the steam passing therethrough and ensures the delivery of dry steam from the nozzles 45 during the tube 70 cleaning operation.

I claim as my invention:

1. The combination of a fire tube boiler, a housing enclosing the same and providing a passage for products of combustion leading from the fire tubes, and a tube cleaning device within said passage in front of the discharge end of said tubes and comprising a steam header, pipes connected to the header and provided with steam discharging nozzles 75 directed toward the open ends of said tubes, a steam separator within said passage in front of the discharge end of said tubes and communicating with the header, a steam supply pipe leading to the separator, and valves for controlling the discharge of steam 80 from the nozzles.

2. The combination of a fire tube boiler, a housing enclosing the same and providing a passage for products of combustion leading from the fire tubes, and a tube cleaning device within said passage in front of the discharge end of said tubes and comprising a horizontally extending steam header 90 having an enlarged portion extending therefrom toward said tubes and exposed to the products of combustion discharged therefrom and forming a steam separator 95 communicating with the rest of the header, a steam supply pipe leading to the separator, pipes connected to the header and provided with steam discharging nozzles directed toward the open ends of said tubes, and valves for controlling the discharge of steam from the nozzles.

3. The combination of a fire tube boiler, a housing enclosing the same and providing a passage for products of combustion leading from the fire tubes, and a tube cleaning device within said passage in front of the discharge end of said tubes and comprising a horizontally extending steam header having an enlarged portion extending downwardly therefrom and exposed to the products of combustion from said tubes and forming a steam separator the upper portion of which is in communication with the rest of the header, a steam supply pipe leading to the upper portion of the separator, a discharge pipe for water of condensation 110 leading from the lower portion of the separator, pipes connected to the header and provided with steam discharging nozzles directed toward the open ends of said tubes, and valves for controlling the discharge of 115 steam from the nozzles.

4. The combination of a fire tube boiler, a housing enclosing the same and providing a passage for products of combustion leading from the fire tubes, said housing having an 130

opening in the front wall thereof normally closed by a hinged door, a tube cleaning device comprising a hollow casting supported by said door between it and the discharge 5 ends of the fire tubes and forming a central steam separating chamber having steam header arms projecting laterally therefrom and communicating therewith, pipes connected to the header arms and provided with 10 steam discharging nozzles directed toward the open ends of the tubes, a steam supply pipe leading to the steam separating chamber, and valves for controlling the discharge of steam from the nozzles.

15 5. The combination of a fire tube boiler, a housing enclosing the same and providing a passage for products of combustion leading from the fire tubes, said housing having an opening in the front wall thereof normally closed by a hinged door, a tube cleaning device comprising a hollow casting supported by said door between it and the discharge 20 ends of the fire tubes and forming a central steam separating chamber having steam header arms projecting laterally therefrom and communicating therewith, hollow fittings screwed into the header arms and communicating therewith, vertical pipes having closed free ends screwed into the hollow fittings and extending upwardly and downwardly therefrom and communicating therewith, branch pipes extending from the vertical pipes and having steam discharging nozzles on their free ends directed toward the open ends of the tubes, a steam supply pipe leading to the steam separating chamber, and valves for controlling the discharge 25 of steam from the nozzles.

30 30 pipe leading to the steam separating chamber, said casting having a baffle formed therein between the steam inlet of the sepa-

rating chamber and the opening affording communication between the separating chamber and the header arms, and valves 35 for controlling the discharge of steam from the nozzles.

6. The combination of a fire tube boiler, a housing enclosing the same and providing a passage for products of combustion leading 40 from the fire tubes, said housing having an opening in the front wall thereof normally closed by a hinged door, a tube cleaning device comprising a hollow casting supported by said door between it and the discharge 45 ends of the fire tubes and forming a central steam separating chamber having steam header arms projecting laterally therefrom and communicating therewith, hollow fittings screwed into the header arms and communicating therewith, vertical pipes having closed free ends screwed into the hollow fittings and extending upwardly and downwardly therefrom and communicating therewith, branch pipes extending from the vertical pipes and having steam discharging nozzles on their free ends directed toward the open ends of the tubes, a steam supply pipe leading to the steam separating chamber, and valves for controlling the discharge 50 of steam from the nozzles.

In testimony whereof I affix my signature hereto.

MARION R. BOWE.
